(57) **CLAIM**

The ornamental design for a club and ball washer with concave upper surface and perimeter splash guard for enhanced water retention, as shown and described herein.

DESCRIPTION

FIG. 1 is a top view of the present invention.

FIG. 2 is a bottom view of the present invention.

FIG. 3 is a back view of the present invention.

FIG. 4 is a front view of the present invention.

FIG. 5 is a left side view of the present invention; and,
FIG. 6 is a perspective view of the present invention with its
ball holder in a raised position.
